ELECTRICAL CIRCUIT WITH ALARM CONTROL DEVICE FOR ALARM CLOCKS

Philip N. Johnson, Turlock, Calif.

Application September 24, 1936, Serial No. 102,385

3 Claims. (Cl. 58—19)

This invention relates to an electrical circuit in conjunction with a special type of alarm control device in an alarm clock and it aims to provide a novel construction embodying parts all contained within the clock case, for illuminating the clock dial incidental to setting of the alarm, which illuminating means is adapted to be extinguished upon shutting off the alarm.

It is further aimed to provide a novel means permitting illumination of the clock dial at any time, as an auxiliary feature.

The more specific objects and advantages will become apparent from a consideration of the description following taken in connection with accompanying drawing illustrating an operative embodiment.

In said drawing:—

Figure 1 is a rear view of a clock embodying my invention, and shown in section on a plane substantially as indicated at 1—1 in Figure 2, to disclose details;

Figure 2 is a side elevation of said clock, broken away to disclose details, and

Figure 3 is a diagram of the electric circuit employed.

Referring specifically to the drawing wherein like reference characters designate like or similar parts, a conventional clock case is illustrated at 10 equipped with clockworks at 11 of any desired form, having an alarm mechanism as at 12, the mechanism being conventional and specifically constituting no part of my invention. However it has a bell or alarm at 13, and an actuating wheel 14, rotatable to actuate the clapper for the bell, and the spring of which mechanism is adapted to be wound by a key 15, preferably removable, and including four prongs 16 which extend interiorly of the clock case.

The present invention includes an electric lamp 17 suitably located within the clock case and adapted to be illuminated when the alarm is set and to stay lit until the alarm goes off and also until the alarm is shut off to illuminate the dial of the clock to facilitate observation. Lamp 17 is detachably connected in a suitable socket 18 and conductors 19 and 20 are connected to the terminals thereof, one leading from a battery or batteries as at 21, having one end or terminal at 22, grounded to the metal clock case 10. The other conductor 20 terminates in a contact 23 positioned rigidly in place by straps 24 secured to the clockworks 11.

Said lamp may be illuminated at any desired time, through the pushing of a switch button 25, located in the front of the clock case, and mount-

ed in a socket or cylinder 26 fastened to the clock case. An expansive spring 27 normally urges the switch to open position. It has a stem 28 and a contact 29, which engages contacts 30, mounted on a suitable insulated support 31 fastened to the case. Said switch is normally open.

A shut-off device for the alarm mechanism is employed at 32 and it consists of a vertical rod 33 slidably mounted in the clock case by means of straps 34 fastened to the works 11 or other suitable parts.

At the top, rod 33 has a lateral extension 35 and a downwardly extending rod 36 preferably capped by a knob 37. Said rod 36 is slidable vertically in the clock case into and out of the path of movement of a lateral projection or pin 38 carried by the wheel 14.

Said arm 33 at its lower end is U-shaped as at 38' and the shorter portion has a resilient contact strip 39 fastened thereto.

It should be borne in mind that the light circuit is not closed when setting the alarm if the alarm is wound first before pulling up on the plunger.

A contact bar 40 is fastened rigidly as by means of a rivet 42 to the works 11.

Normally the alarm mechanism is shut off with the bar 33 and associated parts depressed until the knob 37 engages the top of the clock case and the rod 36 is in the path of movement of the pin 38, thus preventing any movement of the alarm mechanism. Also when the contact blade 39 is in the dotted line position of Figure 1 the plane of said blade crosses the plane of the contact bar 40 intermediate the ends of the latter but the blade 39 is not in contact therewith, the upper end 41 of blade 39 being offset laterally from the blade 40.

In releasing the alarm mechanism for setting thereof, the bar 33 and connected parts are raised to the full line position shown in Figures 1 and 2, the rod 36 freeing the projection 38 and during such elevation of rod 33, a shoulder 41 engages the contact 40, placing the free end thereof under tension, such contact 40 being fastened at one end 42 to the works 11. An offset guard projection 41' on blade 39 extends above shoulder 41. Thereafter, when key 15 is rotated, the adjacent prong 16, into the path of movement of which spring contact 39 has been elevated, will engage the latter, move it laterally out of engagement with the shoulder 41, the contact 40 springing back to normal position, abutting one side of the contact blade 39 as shown in full lines in Figures 1 and 3, engaging it with the contact 23 and maintaining such

engagement. As a result, an electric circuit is closed through the lamp 47, illuminating the dial or face of the clock. The illumination persists until the arm 33 and associated parts are again depressed, usually after the sounding of the alarm. Thus the light is lit when the alarm is set and it stays lit until the alarm goes off and also until the alarm is shut off.

It will be clear that in the winding of the spring 10 for the alarm mechanism, that the prong 16 may readily pass the free end of the contact 39, dis- placing it since it is resilient.

Various changes may be resorted to provided they fall within the spirit and scope of the in- 15 vention.

I claim as my invention:—

1. In combination with a clock having an alarm mechanism, a winding mechanism therefor, illuminating means for the clock, an electric circuit for the illuminating means, a movable shut- off device for the alarm mechanism, a contact in said circuit, a second contact, said movable shut-off device having a contact blade normally disengaged from said contacts, said contact blade 20 having a shoulder engageable with the first contact to tension the latter when the shut-off device is moved to released position, said blade in the latter position extending into the path of winding movement of a part of the winding mechanism whereby the contact blade will be moved beyond one end of the first mentioned contact and into engagement with the second mentioned contact, with the first mentioned contact returning to normal position and maintaining the blade 25 in engagement with both contacts.

2. In combination with a clock having an alarm mechanism, a winding mechanism therefor, illuminating means for the clock, an electric circuit for the illuminating means, a movable shut- off device for the alarm mechanism, a contact in 30 said circuit, a second contact, said movable shut-

off device having a contact blade normally disengaged from said contacts, said contact blade having a shoulder engageable with the first contact to tension the latter when the shut-off device is moved to released position, said blade in the latter position extending into the path of winding movement of a part of the winding mechanism whereby the contact blade will be moved beyond one end of the first mentioned contact and into engagement with the second mentioned contact, 10 with the first mentioned contact returning to normal position and maintaining the blade in engagement with both contacts, said shut-off device having a depending rod, and said alarm mechanism including a rotatable part having a 15 projection into the path of movement of which said rod is adapted to extend.

3. In combination with clockworks having an alarm mechanism including a rotatable part provided with a projection, a key for winding said 20 mechanism having a stud, a vertically movable arm provided with a depending rod adapted for disposition in the path of movement of said projection to shut off the alarm, an upwardly ex- 25 tends resilient contact blade on said arm having a shoulder, illuminating means for the dial of the clock, an electric circuit means within the clock for said illuminating means having a re- silient contact and a second contact, the first contact in the raised position of said arm being 30 engaged and tensioned by said shoulder, said contact blade being engageable by said stud when in the raised position to slide it off the first contact so that the latter will intercept its return to normal position and will maintain it in engagement 35 with the second contact, said contact blade being in contact with the resilient contact after said resilient contact is slid off the shoulder of the contact blade.

PHILIP N. JOHNSON.
